AUTOMATIC COAL STOKER

George E. Valentine and John I. Hurst,
Schuylkill Haven, Pa.

Application November 20, 1939, Serial No. 305,342

1 Claim. (Cl. 110—109)

This invention relates to automatic coal stokers and has for an object to provide in a device of this character an inclined grate having perforations of greater dimension at the bottom than at the top through which a forced draft may be blown to more effectively promote combustion than in similar devices.

A further object is to provide apparatus of this type including a notched step actuated roll at the bottom of the grate for removing ashes and also for preventing coal from sliding off the grate so that a uniform coal bed will be effected.

A further object is to provide apparatus of this type having a step actuated pusher head which may be adjusted to feed the fuel at any pre-determined rate so that more uniform combustion will be obtained than hitherto possible.

A further object is to provide apparatus of this character having a pipe for carrying away obnoxious fumes and also to enable the apparatus to hold the fire when the motor is not running.

A further object is to provide apparatus of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a longitudinal sectional view, with parts in elevation, of an automatic coal stoker constructed in accordance with the invention.

Figure 2 is a plan view of the apparatus shown in Figure 1, with the boiler, hopper and fume pipe removed.

Figure 3 is a side elevation of the stoker showing the ratchet drive for the pusher head and notched roll.

Figure 4 is a plan view of the grate.

Figure 5 is a side elevation of the driving disk and wrist pin.

Figure 6 is a cross sectional view of the disk shown in Figure 5.

Figure 7 is a cross sectional view taken on the line 1—7 of Figure 3.

Referring now to the drawings in which like characters of reference designate similar parts

in the various views, a preferred embodiment of the invention is shown, in which 10 designates a box-like base of substantially rectangular contour having an integral shelf 11 braced by legs 13 at the rear of the base, and supporting the main operating units, namely, an electric motor 12, a fan 13, and a speed reduction unit 14, these parts being conventional. The base also serves as an ash pit and is provided with an opening 15 and door 16 in the front for the removal of ashes.

The top portion of the base is adapted to support a cylindrical firebox 17 which is provided with an inclined grate support 18 on the inside and with a pusher box 19 on the outside, both preferably being formed integral with the firebox. A fuel supply hopper 9 is mounted on the top of the pusher box.

The grate 20 is disposed between the side members 21 of the grate support, both the grate and the chute being mounted at an appropriate angle to the horizontal to facilitate movement of the coal downward over the grate, as best shown in Figure 4. The grate is provided with a plurality of air ports 22, and the head end 23 of the grate is curved and beveled so as to make a close fit against the curved surface of the inside of the firebox. The head end of the grate rests upon a ledge 24 formed integral with the firebox and likewise the foot or lower end 25 of the grate rests upon a ledge 26 formed integral with the grate support 18. While the grate is shown as consisting of a single unit it is understood that it may be made in sections for the larger sizes of stokers. The front of the firebox is provided with an extension 27 and with a door 28 for kindling, cleaning and inspection.

It will be seen by referring to Figures 1 and 2 that the fan 13 is provided with an outlet pipe 29 which enters the wall of the firebox underneath the grate to direct a forced draft upwardly through the grate to promote combustion. The fan is also provided with an adjustable circular baffle disk 30 at the intake opening to permit adjustment of the air supply.

A conventional vertical type flue boiler 31 is mounted on top of the fire box 17 but other types of boilers may be used. The smoke pipe 32 is provided with a damper 33 as usual, and a secondary pipe 34 leads from the top of the pusher box 19 into the smoke pipe 32 and carries off obnoxious fumes that may result from the use of wet fuel. This fume pipe is equipped with a damper 35 to permit combustion being controlled when the motor is not running.

A notched roll 36 is mounted on a step driven shaft 37 which is journalled in bearings in the base 10 at the bottom of the grate support. The roll is driven at a pre-determined rate of speed 5 to remove ashes, and projects to about the same height as the side members 21 of the grate support to form a closure at the bottom of the grate support above the grate adapted to prevent live fuel from sliding off the inclined grate, and to 10 maintain a pre-determined depth of the fuel bed. The shaft 37 projects at one end exteriorly of the base 10 and is terminally equipped with a fine tooth ratchet wheel 38.

The speed reduction unit 14 steps down the 15 high speed of the motor 12 and imparts slow speed to the final shaft 39 of the reduction gear train. The shaft 39 is equipped with a crank disk 40, best shown in Figures 5 and 6.

The crank disk 40 is provided with a slot 41 20 which extends from the hub 42 to the periphery of the disk. An H block 43 is mounted in the slot and is provided with a threaded opening to receive an adjusting screw 44 which is uniformly reduced at its inner end as shown at 45 to receive 25 a plunger 46 mounted in an opening 47 in the hub. A helical spring 48 is confined in the opening back of the plunger by a screw 49. By turning the adjusting screw 44 the throw of the crank pin 50 carried by the block may be varied.

30 A rock shaft 51 is journalled in the sides of the pusher box and is provided inside the box with a pair of rocker arms 52. The shaft is provided outside the pusher box with a rocker arm 53. A fuel pusher, in the nature of a thick plate 54, is 35 disposed transversely of the pusher box and rests upon the bottom thereof adjacent to the top of the grate 20. The fuel pusher is connected to the rocker arms 52 by a pair of rods 55.

A rocker arm 56, best shown in Figure 7, is 40 mounted upon a sleeve 57 which is secured by a set screw 58 to a boss formed on the base 10 and forms a bearing for the ratchet wheel shaft 37. The rocker arm carries a pawl 59 which engages 45 the teeth of the ratchet wheel 38 to impart step motion through the ratchet wheel to the notched roll 36 at the bottom of the grate.

The crank pin 50 of the crank disk 40 and the outer end of the rocker arm 56 are connected together by a link 60 to permit the ratchet wheel 50 being driven by the crank disk. A link 61 connects the rocker arm 53 which is outside the pusher box 19, with the rocker arm 56. A single pin 57 is shown as connecting the links 60 and 61 to the rocker arm 56 and this pin forms a pivot 55 for the pawl 59. When the ratchet wheel is driven by the crank disk, the link 61 imparts step motion to the fuel pusher 54 and simultaneously the

ratchet wheel imparts step motion to the notched roller 36.

A baffle plate 62 is adjustably mounted on the front wall of the pusher box by adjusting screws 63 passed through slots 64 in the plate and engaged in the front wall of the pusher box. The baffle plate regulates the depth of the fuel bed at the top of the grate.

In operation the fan delivers a current of air to the compartment in the base under the grate 10 and through the tapered air ports 22 in the grate to produce a forced draft through the coal bed. The motor imparts motion through the speed reduction unit 14, to the crank disk 40, crank pin 50, and through the link 60 to the rocker arm 56 and pawl 59. Forward motion of the pawl imparts motion to the ratchet wheel 38, shaft 37 and notched roll 36. On its forward motion the pawl also imparts movement through the link 61 to the rocker 53, pair of rods 55 to the fuel 20 pusher 54. The latter urges a small quantity of fuel to move down over the grate. At a certain pre-determined temperature a thermostat (not shown) stops the motor for a period that may have considerable range and then starts the motor again, thus promoting economy in electric current as well as fuel.

From the above description it is thought that the construction and operation of the invention will be fully understood without further explanation.

What is claimed is:

A coal stoker comprising the combination with a fire box, of a base supporting the fire box forming an ash pit, a grate in the fire box sloping downwardly from the rear of the fire box to the base, a pusher box extending in alinement with the grate on the rear of the fire box, a hopper communicating with the pusher box, a notched roll supported by the base at the bottom of the grate and extending above the grate for preventing coal from sliding off the grate, a reciprocatory pusher in the pusher box for feeding coal from the hopper onto the grate, means for effecting a forced draft upwardly through the grate, a ratchet wheel connected to the notched roll, an electric motor, a speed reduction unit connected to the motor, a crank disk connected to the unit having an adjustable wrist pin, a link connected to the wrist pin, a pawl connected to the link and engaging the ratchet wheel for imparting step rotation to the ratchet wheel, a second link connected to the first named link and extending upwardly therefrom, and a crank connecting the second named link with the pusher for reciprocating the pusher.

GEORGE E. VALENTINE.
J. I. HURST.
